UNITED STATES PATENT OFFICE.

RALPH H. PIERCE AND GEORGE A. ANDERSON, OF EUGENE, OREGON.

DISK WHEEL.

Application filed August 3, 1926. Serial No. 126,874.

This invention relates to a disk wheel and a demountable rim therefor.

An object of the invention is the provision of a disk wheel having a demountable rim which may be readily removed from the wheel by the rotation of a crank.

A further object of the invention is the provision of a demountable rim for a disk wheel in which an expanding flanged shoe 10 is controlled by a crank for locking the rim to the felly of the wheel, the shoe being slidable on rivets which not only support the shoe but provide means for securing the disked sections of the disk wheel.

This invention will be best understood from a consideration of the following detailed description, in view of the accompanying drawings forming a part of the specification; nevertheless it is to be understood that the invention is not confined to the disclosure, being susceptible of such changes and modifications which shall define no material departure from the salient features of the invention as expressed in the appended claims.

In the drawings:

Figure 1 is a view in elevation of a wheel and rim, constructed according to the principles of our invention.

Figure 2 is a section of the wheel taken along the line 2—2 of Figure 1.

Figure 3 is a view in elevation of one section of the disk wheel with the securing rivets shown in section.

Figure 4 is a sectional elevation of the locking crank.

Figure 5 is a section of the locking crank taken along the line 5—5 of Figure 4.

Figure 6 is a section of the shoe taken along the line 6—6 of Figure 3.

Figures 7 and 8 are sections similar to the section shown in Figure 6 and taken respectively on the lines 7—7 and 8—8 of Figure 3.

Figure 9 is a transverse section of a modified form of a locking crank.

Figure 10 is a section of the locking crank taken along the line 10—10 of Figure 9.

Referring more particularly to the drawings, 10 and 11 designate a pair of steel disks secured together adjacent their peripheries by a plurality of spacer rivets 12 and a plurality of spacer rivets 13 which are square in cross section. A circular wood

filler 14 is secured in position at the center and between and to the disks 10 and 11.

Disk 10 has a lateral curved flange 15 extending for substantially the half of the periphery of said disk. Said flange is provided with a groove 16 adapted to receive a bead 17 on the rim 18. A second flange 19 extends around the remaining portion of the periphery of the disk and is adapted to engage the inner face of the band and at one side of the bead 17 extending inwardly from a curved edge of the flange 15 is a flange 20, coextensive with the flange 15. The disk 11 adjacent its periphery is in abutment with the flange 15. The rivets 12 secure this engaged portion of the disk 10 to disk 11 while the rivets 13 not only secure the remaining portions of the disks 10 and 11 but space the remaining portions of the disks from each other to permit movement of a shoe 21.

The shoe is curved to conform to the curvature of the periphery of the rim 18 and is of a length to permit shifting of the shoe thereby providing a space between the ends of the shoe and the ends of the curved flange 20. The shoe has a flange 22 and a flange 23 of less width than the flange 22, the flanges being connected together by a curved rim 24 having a groove 25. Referring to Figures 6 to 8 inclusive, it will be seen that the groove is in concentric relation with the plane passing through the center of the bead 17 of the rim 18 and at right angles to the axis of the wheel.

The flanges 22 and 23 of the shoe 21 are provided with slots 26 located at acute angles to radii passing through the rivets 13 and the rivets pass through said slots. By this construction, the shoe is movable eccentrically relative to the portion of the rim 18 adjacent the shoe and away from the rim. Said shoe is located between portions of the disks 10 and 11 and is adapted to seat the flange 19 of disk 10 in a portion of the groove 25 of the shoe.

A crank 27 is journaled in apertures in the disks 10 and 11 intermediate the ends of the shoe. A square head 28 projects beyond disk 11 and is adapted to be engaged by a suitable wrench for rotating the crank. A rod 29 is pivotally connected at 30 to the crank and is received by a sleeve 31 threaded into a perforation in a bolt 32. The sleeve is adjusted on the rod 29 between

the shoulders 33 and 34. The bolt is mounted in the flanges 22 and 23 of the shoe. Said shoe is cut away at 35 at each side of the crank 27 to permit movement of the shoe 5 between the disks 10 and 11.

A locking spring 36 is secured to the outer face of disk 11 adjacent the crank 27 and has an opening 37 conforming to the shape of the head 28 in order that the head may be 10 received by the opening and hold the crank from turning. The spring may be pressed inwardly towards the disk 11 until the opening registers with the cylindrical portion 38 of the crank when the crank is free for 15 turning.

The disk 11 is provided with an opening 39 and is of sufficient diameter to permit the usual valve stem 40 of an inner tube to project above the outer edge of the opening. 20 A cap is adapted to be applied to the threaded end of the valve stem to operate as a dust cap.

A weight 50 is secured in any approved manner to the disks, diametrically opposite 25 the crank 27 as a counterbalance.

A driving pin 51 on the rim is inserted through an opening in the flange 15 of disk 10.

The operation of our device is as follows: 30 The rim 18 is so placed that the bead 17 will be engaged by the groove 16 of the flange 15 on the disk 10.

The opposite side of the rim is moved so 35 that the bead 17 at this point will engage the flange 19 on disk 10. The crank 27 is rotated by the wrench which has been applied to the head 28. The rotation of the crank causes the rod 29 to exert a pull on bolt 32 and since said bolt is connected to the shoe 40 21, said shoe is forced into engagement with the rim, said shoe being guided by the rivets 13 and the slots 26.

When the shoe is positioned, it is forced up rigidly against the rim as the bead 17 of the 45 rim is seated under pressure in the groove 25. The rim springs away from the felly of the wheel adjacent the crank 27 when the shoe has been released by a reverse rotation of the crank.

50 It must be borne in mind that the spring 36 must be depressed towards the disk 11 so that the opening 37 will be positioned at the reduced cylindrical portion 38 before the crank may be rotated, since the opening 55 engages the head 28 and locks the crank from rotation after the crank has been moved to releasing or locking position of said shoe.

The groove 25 is displaced relative to a 60 plane passing vertically and midway between the sides 22 and 23 of the shoe so that the shoe will grip the inner side of the flange 19 on disk 10 and also grip bead 17 of the rim when the shoe is forced into place and this is true of the grooves 25^a and 25^b as 65 shown in Figures 6 to 8 inclusive.

In Figures 9 and 10, a modified form of the invention is shown and in which a crank 27^a is journaled in apertures in the disks 10^a and 11^a intermediate the ends of the shoes. A square head 28 projects beyond the disk 11^a and is adapted to be engaged by a suitable wrench for rotating the crank. A rod 29^a is pivotally connected at 30^a to the crank and has one end as shown at 46 inserted through a perforation in a bolt 32^a. The bolt is mounted in flanges 22^a and 23^a of the shoe. A ring 47 mounted in a groove at the outer end of the rod 46 engages a shoulder 48 in the bolt 32^a and maintains the rod against loss from the bolt. A spring 45, 70 75 80 embracing the rod 46, tends to exert a predetermined pressure between the bolt 32^a and a shoulder 49 formed on the rod 46. This spring affords a cushioning effect and permits an easier operation of the locking device, especially when the wheel is covered with dirt or sand. As the sand works out the rim is automatically tightened by the 85 spring which forces the shoe outwardly. The spring eliminates the use of an adjustment as shown in Figures 4 and 5.

What we claim is:

1. In a disk wheel, the combination with a wheel felly having a groove for a portion of the periphery thereof, a rim having an annular bead adapted to seat within the groove, an arcuately shaped shoe having a groove distorted relative to a plane curve passing transversely of the bead on the rim, means for movably supporting the shoe, and means for moving the shoe into engagement with the rim so that the distorted groove in the shoe will be forced to receive the bead on the rim and positively lock the rim to the wheel. 90 95 100

2. In a disk wheel, the combination with a wheel felly having a groove for a portion of the periphery thereof, a rim having an annular bead adapted to seat within the groove, an arcuately shaped shoe having a groove distorted relative to a plane curve passing transversely of the bead on the rim, means for movably supporting the shoe, and means for moving the shoe into engagement with the rim so that the distorted groove in the shoe will be forced to receive the bead on the rim and positively lock the rim to the wheel, said felly being cut away opposite the groove in the felly to permit movement of the shoe for engaging the rim for adjusting the flanges in the grooves and radially of the body member. 110 115 120

3. In a disk wheel, the combination with a wheel felly having a groove for a portion of the periphery thereof, a rim having an annular bead adapted to seat within the groove, an arcuately shaped shoe having a groove distorted relative to a plane curve passing transversely of the bead on the rim, means for movably supporting the shoe, and 125 130

means for moving the shoe into engagement with the rim so that the distorted groove in the shoe will be forced to receive the bead on the rim and positively lock the rim to the wheel, said supporting means consisting of rivets and slots in the shoes to receive said rivets.

4. In a disk wheel, the combination with a wheel felly having a groove for a portion of 10 the periphery thereof, a rim having an annular bead adapted to seat within the groove, an arcuately shaped shoe having a groove distorted relative to a plane curve passing transversely of the bead on the rim, means 15 for movably supporting the shoe, and means for moving the shoe into engagement with the rim so that the distorted groove in the shoe will be forced to receive the bead on the rim and positively lock the rim to the wheel, 20 said supporting means consisting of rivets and slots in the shoes to receive said rivets, said slots being inclined at an acute angle to radii passing transversely through the slots so that the shoes will be moved transversely 25 of the radii and towards or away from the rim.

5. In a disk wheel, the combination with a wheel felly having a groove for a portion of its periphery thereof, a rim having an annular bead adapted to seat within the groove, 30 an arcuately shaped shoe having a groove adapted to receive the remaining portion of the bead on the rim, said shoe having a plurality of spaced slots extending transversely 35 of radii passing through said slots, rivets carried by the wheel and received by said slot, a crank rotatably mounted in the felly, a rod connected with the crank, a bolt rotatably mounted in the shoe, and means for connecting the bolt with the rod so that when the crank is revolved the shoe will be moved into engagement with the rim.

6. In a disk wheel, the combination with a wheel felly having a groove for a portion of 45 its periphery thereof, a rim having an annular bead adapted to seat within the groove, an arcuately shaped shoe having a groove adapted to receive the remaining portion of the bead on the rim, said shoe having a plurality of spaced slots extending transversely 50 of radii passing through said slots, rivets carried by the wheel and received by said slot, a crank rotatably mounted in the felly, a rod connected with the crank, a bolt rotatably mounted in the shoe, means for connecting the bolt with the rod so that when 55 the crank is revolved the shoe will be moved

into engagement with the rim, said connecting means between the rod and the bolt consisting of a sleeve threaded into the bolt, 60 said sleeve being adjustable in the bolt for shortening the connection between the bolt and the crank through the rod.

7. In a disk wheel, the combination with a wheel felly having a groove for a portion of 65 its periphery thereof, a rim having an annular bead adapted to seat within the groove, an arcuately shaped shoe having a groove adapted to receive the remaining portion of the bead on the rim, said shoe having a plurality of spaced slots extending transversely 70 of radii passing through said slots, rivets carried by the wheel and received by said slot, a crank rotatably mounted in the felly, a rod connected with the crank, a bolt rotatably mounted in the shoe, means for connecting the bolt with the rod so that when the crank is revolved the shoe will be moved into engagement with the rim, and a spring cushioning means between the bolt and the rod. 80

8. In a disk wheel, the combination with a wheel felly having a groove for a portion of 85 its periphery thereof, a rim having an annular bead adapted to seat within the groove, an arcuately shaped shoe having a groove adapted to receive the remaining portion of the bead on the rim, said shoe having a plurality of spaced slots extending transversely 90 of radii passing through said slots, rivets carried by the wheel and received by said slot, a crank rotatably mounted in the felly, a rod connected with the crank, a bolt rotatably mounted in the shoe, means for connecting the bolt with the rod so that when the crank is revolved, the shoe will be moved into engagement with the rim, a spring embracing the rod, said rod having a shoulder, 95 the spring being maintained under pressure between the shoulder and the bolt.

9. In a disk wheel, the combination with a wheel felly having a groove for a portion of the periphery thereof, a rim provided with a bead adapted to seat within the groove, locking means provided with a groove distorted relative to the plane curve passing transversely of the bead on the rim, and means for moving the locking means into engagement with the rim so that the distorted groove in the locking means will be forced to receive the bead on the rim and positively 100 lock the rim to the wheel. 105
